UNITED STATES PATENT OFFICE

FRANK BARBER, OF COLLEGE POINT, NEW YORK

PROCESS OF MAKING PLAITED LEATHER

Application filed February 27, 1929. Serial No. 342,961.

My invention relates particularly to a process of plaiting leather so as to produce plaited leather sheets suitable for use for any desired purpose, but particularly in connection with the manufacture of shoes and product thereof.

The object of my invention is to provide a process whereby sheets of plaited leather may be readily produced and at a cost within the range suitable for utilization in the manufacture of leather products, particularly shoes. A further object is to provide such a process which may be carried out expeditiously and at comparatively little cost, while at the same time producing a product which is of great uniformity and of such compactness and with its edges finished in such a manner as to securely hold the different portions of the sheet of plaited leather in a fixed position until it is finally utilized for the manufacture of the finished product, as, for example, shoes, etc. Further objects will appear from the detail description of my invention hereinafter.

While my invention is capable of embodiment in many different forms, by way of illustration I shall describe only certain forms of my invention hereinafter, and while it is capable of being carried out in connection with many different types of apparatus, I have shown only one type of apparatus for use in connection therewith in the accompanying drawings, in which—

Fig. 1 is a front elevation of a machine used in accordance with my invention showing diagrammatically the number of strip-supporting levers therein;

Fig. 2 is a side elevation of the same;

Fig. 3 is an enlarged rear elevation of a portion of the operating mechanism;

Fig. 4 is an enlarged detail of the leather shown in the process of being plaited;

Fig. 5 is an elevation of the transverse supporting bar for the strips of leather;

Fig. 6 is an enlarged front elevation showing one of the arms holding the slotted ends of the leather strips;

Fig. 7 is a plan view of the knife used in the process;

Fig. 8 is a plan view of one of the leather

bands used for making the vertical strips of leather;

Fig. 9 is an elevation showing the band of leather used for making the transverse strips; and

Fig. 10 is a transverse section of the plaited leather having thereon a fabric backing.

In the drawings, I have shown a main frame 1 having a base 2 for supporting a mechanism which may be used in carrying out my process. This comprises a foot treadle 3 carried by a pivot rod 4 which passes through the frame 1 in such a manner that the treadle 3 will be supported in an opening 5 in the middle of the frame 1 near the bottom thereof. The rear end of said treadle 3 has a slot 6 to receive one end of an operating rod 7 connected to said treadle by means of a bolt 8. Said rod 7 extends upwardly along the rear of the frame 1 and is connected at its upper end by a bolt 9 to two flaring arms 10 and 11 which are in turn connected by a transverse bolt 12 to the two lower ends of links 13 and 14, which are normally retained in an upward position by springs 15 and 16 connected at their lower ends to the rod 12 and at their upper ends to the rear of the frame 1 by means of eyelets 17 and 18. These links 13 and 14 are flared outwardly, as shown in Fig. 3, so as to pass through openings 19 and 20 formed by guide bars 21 and 22 which are attached by bolts 23 to the frame 1, spacing blocks 24 being interposed between said frame and the ends of the guide bars 21 and 22. In front of the frame 1 said links 13 and 14 also pass through U-shaped guide brackets 25 and 26, which are supported upon a transverse plate 27 bolted to the front face of the frame 1. At their extreme upper ends the links 13 and 14 are pivotally connected by two rear links 28 and 29, by means of pivot rods 29a and 29b, to a transverse supporting bar 30 carrying thereon thirty-seven arms 31, each of which is provided with a lower hooked end 32 for receiving the free ends of a corresponding number of vertical leather strips 33 having slits 34 cut into their ends for this purpose. These hooked arms 31 are pivotally supported upon a rod 35 which, after passing through the arms, is pivotally supported in

the two U-shaped brackets where they are held in place by means of nuts 36. Also, at the upper ends of the links 13 and 14 there extend downwardly two front links 37 and 38 which are connected at their lower ends to a transverse pivoted rod 39 carrying thirty-seven right-angularly shaped arms 40 which alternate in position between the series of arms 31 and are likewise pivotally supported upon the rod 35. These right-angle arms 40 are also provided with hooks 41 at their lower ends to receive the other free ends of the leather strap 33, which are also provided with slits 34 for this purpose.

15 These leather strips 33 are introduced into the machine by passing them over a lower supporting bar 42, said bar 42 having hooked portions 44 and 45 at the two ends thereof to receive a branched cord 46, the lower end of which is connected to a pin 47 just above the opening 5.

20 The vertical strips 33 are made from a composite band of leather 48 made up of two short bands 49 and 50 sewn together at their ends by three transverse rows of stitching 51. The composite band of leather 48 is cut into strips longitudinally by any suitable mechanism so as to obtain therefrom the vertical strips 33 of the required length and 25 width, the widths of the strips being entirely uniform throughout.

25 The vertical strips of leather 33 are inserted in this manner into the apparatus in such a way that the adjacent ends of each strand 35 will present the same finished face of leather to the front towards the operator, this being accomplished by giving the rear end of the vertical strip 33, which passes over the rear side of the bar 42, a 180° turn, as shown in 40 Fig. 4, for this purpose. After the longitudinal strips have thus been placed in the apparatus the treadle 3 is operated to reverse the position of the ends of the longitudinal strips so as to draw the upper end of the 45 links 13 and 14 downwardly into the dotted line position, as shown in Fig. 2. This has the effect of moving the upper ends of the right-angle arms 40 forwardly and the upper ends of the arms 31 rearwardly so that 50 the positions of the lower hooked ends of said arms 40 and 31 are reversed, thus throwing the ends of the longitudinal strips, which were formerly to the front, now to the rear, while the rear ends thereof now occupy the 55 position previously taken by the other ends thereof. A knife 52, having tapered slits 53 and 54, is then inserted in a space 55 between the two layers of longitudinal strips and lowered until it cannot be moved any farther 60 in view of the tautness of the longitudinal strips 33, which are tightly held down by the bar 42 and the cord 46. When the knife 52 has been moved into this position the longitudinal strips 33 will be preliminarily 65 adjusted so as to see that all of them present

towards the front the finished face of the leather. Meantime, a number of transverse strips 56 are formed from a short band of leather 57 so as to produce simultaneously therefrom a number of such strips of uniform width and which are equal in width and thickness to the longitudinal strips 33, but of considerably shorter lengths. One end of a transverse strip 56 is then caught in one of the slits 53, 54, in the knife 52, and said knife moved transversely from between the two layers of vertical strips 33 so that said transverse strip 56 occupies the place formerly taken by the knife 52 with one end thereof protruding only a small distance from the side of the outermost vertical strip 33 and the other long end extending beyond the other side of the series of vertical strips. Thereupon, the treadle 3 is released to again reverse the position of the longitudinal layers of strips. The knife 52 is again inserted in the space 55 and moved downwardly until it is adjacent to the transverse strip 56 already inserted between the vertical strip 33. The free end of said strip 56 is now 70 caught in the slit in the adjacent end of the knife, care being taken to attach the end of the transverse strip therein in such a manner that it will make a 180° turn in order to bring the finished face of the leather again to the front, when the knife is again removed transversely from between the longitudinal strips, thus bringing the free end of the transverse strip out to the same side as the other end of said strip. The treadle 3 is again operated to shift the upper ends of the longitudinal strips into the reverse position, whereupon the knife 52 is again inserted between the same and a second transverse strip 75 attached so as to bring its finished side face outwardly to the front, when the knife is withdrawn, but in the opposite direction from the withdrawal of the knife in the first insertion operation of the transverse strip, so that the front end of the second strip protrudes from the opposite side from that where the free end of the first strip inserted was located. After again shifting the upper ends of the longitudinal strip 33 with the treadle 3, the knife is again inserted and engaged with 80 the free end of the second transverse strip, after the same 180° turn therein, and said free end drawn through to the side occupied by the other end of said strip. In this way transverse strips are introduced in succession with the free ends of adjacent strips protruding at opposite sides until an entire plaited sheet of leather is obtained in which the position of the parts is retained due to the alternating location of the free ends of the 85 transverse strips. Thereupon the cord 46 is disengaged, the bar 42 removed and the upper ends of the sheet of plaited leather removed from the machine by lifting the slotted ends off from the hooks 32 and 41. These 90

slitted ends are then clipped off and a brush with rubber cement is brushed over these free ends so that the rubber, which quickly dries thereon, holds securely the free edge in place. 5 If desired, the other looped ends which have formerly been retained by the bar 42, may be given a similar treatment with the rubber cement, although this is not essential because of the loops which are in this end of the 10 fabric. Before applying the rubber cement to this end of the fabric the looped ends may be cut off, if desired. Finally, before the fabric is used in the manufacture of shoes it is provided with a backing cloth 58, which 15 is a woven fabric of any desired character, having a facing of rubber cement 59 which causes it to adhere to the plaited leather fabric.

In making fabrics in this way it will be understood that many combinations and color effects may be obtained by choosing strips of different colors for the longitudinal and transverse strips respectively, and that, also, the longitudinal, as well as the transverse 25 strips, may be alternated in various colors, thus obtaining very desirable color effects in the resulting leather sheet.

While I have described my invention above in detail I wish it to be understood that many 30 changes may be made therein without departing from the spirit of the same.

I claim:

1. The process which comprises producing a plaited sheet of leather by doubling a series of longitudinal strips of leather, supporting the doubled ends in a series and the other ends of said strips in two widely separated series with the free-end portion of the strip, which is adjacent to the free-end portion of the next strip, located in a different series therefrom, and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said 50 transverse strip between said series.

2. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom and then introducing transverse strips of leather so that successive transverse strips are located with the loop against alternating edges of the series of longitudinal strips between said longitudinal strips by inserting one free-end of a transverse strip, reversing the relative positions 60 of the two series of ends of the longitudinal strips, and then inserting the remaining end of said transverse strip between said series.

tions of the two series of ends of the longitudinal strips, and then inserting the remaining end of said transverse strip between said series, this being accomplished by engaging and drawing the free ends of said transverse strips through the series of free-ends of the longitudinal strips as they are shifted from one position to the other. 70

3. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom, said two series of free-ends being located so as to present to the front the same face of each leather strip and then introducing transverse strips of leather so that successive 85 transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series with the same face on both ends of the transverse strip presented to the front. 90

4. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom, said two series of free-ends being located so as to present to the front the same face of each leather strip, and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series with the same face on both ends of the transverse strip presented to the front, this being accomplished by engaging and drawing the free-ends of said transverse strips through the series of free-ends of the longitudinal strips as they are shifted from one position to the other. 100

5. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip, located in a different series therefrom, 110

and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series, and then securing together the ends of the longitudinal strips.

6. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips and then inserting the remaining end of said transverse strip between said series, this being accomplished by engaging and drawing the free ends of said transverse strips through the series of free-ends of the longitudinal strips as they are shifted from one position to the other, and then securing together the ends of the longitudinal strips.

7. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom, said two series of free-ends being located so as to present to the front the same face of each leather strip and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series with the same face on both ends of the transverse strip presented to the front and then securing together the ends of the longitudinal strips.

8. The process which comprises producing a plaited sheet of leather by doubling a series of longitudinal strips of leather, supporting the doubled ends in a series and the other ends of said strips in two widely separated series with the free-end portion of the strip which

is adjacent to the free-end portion of the next strip located in a different series therefrom, said two series of free-ends being located so as to present to the front the same face of each leather strip, and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series with the same face on both ends of the transverse strip presented to the front, this being accomplished by engaging and drawing the free-ends of said transverse strips through the series of free-ends of the longitudinal strips as they are shifted from one position to the other, and then securing together the ends of the longitudinal strips.

9. The process which comprises producing a plaited sheet of leather by doubling a series of longitudinal strips of leather, supporting the doubled ends in a series and the other ends of said strips in two widely separated series with the free-end portion of the strip, which is adjacent to the free-end portion of the next strip, located in a different series therefrom, and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series, and then securing together the ends of the longitudinal strips with rubber cement.

10. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips and then inserting the remaining end of said transverse strip between said series, this being accomplished by engaging and drawing the free ends of said transverse strips through the series of free-ends of the longitudinal strips as they are shifted from one position to the other, and then secur-

ing together the ends of the longitudinal strips with rubber cement.

11. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom, said two series of free-ends being located so as to present to the front the same face of each leather strip and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series with the same face on both ends of the transverse strip presented to the front and then securing together the ends of the longitudinal strips with rubber cement.

12. The process which comprises producing a plaited sheet of leather by doubling a series of longitudinal strips of leather, supporting the doubled ends in a series and the other ends of said strips in two widely separated series with the free-end portion of the strip which is adjacent to the free-end portion of the next strip located in a different series therefrom, said two series of free-ends being located so as to present to the front the same face of each leather strip, and then introducing transverse strips of leather so that successive transverse strips are located with the loops against alternating edges of the series of longitudinal strips between said longitudinal strips by inserting one free-end of a transverse strip, reversing the relative positions of the two series of ends of the longitudinal strips, and then inserting the remaining end of said transverse strip between said series with the same face on both ends of the transverse strip presented to the front, this being accomplished by engaging and drawing the free-ends of said transverse strips through the series of free-ends of the longitudinal strips as they are shifted from one position to the other, and then securing together the ends of the longitudinal strips with rubber cement.

13. A sheet of plaited leather comprising a series of parallel strips running in one direction and a series of interwoven flat leather strips running cross-wise of the first-mentioned strips, the last-mentioned strips being located with a doubled end at one side, so doubled as to locate the same face of the flat strip throughout at the same side of the sheet of leather, and free ends at the other side of said sheet of leather, with the ad-

jacent strips having their doubled ends against opposite sides of said sheet of leather and the two ends of the doubled strip being adjacent to each other.

14. A sheet of plaited leather comprising 70 a series of parallel strips running in one direction and a series of interwoven flat leather strips running cross-wise of the first-mentioned strips, the last-mentioned strips being located so that the two halves thereof are interwoven adjacent to each other in the sheet of leather with a doubled end at one side, so doubled as to locate the same face of the flat strip throughout at the same side of the sheet of leather, and free ends at 75 the other side of said sheet of leather, with the adjacent strips having their doubled ends against opposite sides of said sheet of leather.

15. A sheet of plaited leather comprising 80 a series of parallel strips running in one direction, a series of interwoven flat leather strips running cross-wise of the first-mentioned strips, the last-mentioned strips being located with a doubled end at one side, so doubled as to locate the same face of the 85 flat strip throughout at the same side of the sheet of leather, and free ends at the other side of said sheet of leather, with the adjacent strips having their doubled ends against opposite sides of said sheet of leather and the two ends of the doubled strip being adjacent to each other, and an adhesive layer 90 applied to the free ends of a series of strips.

16. A sheet of plaited leather comprising 95 a series of parallel strips running in one direction, a series of interwoven flat leather strips running crosswise of the first-mentioned strips, the last-mentioned strips being located so that the two halves thereof are interwoven adjacently to each other in 100 the sheet of leather with a doubled end at one side, so doubled as to locate the same face of the flat strip throughout at the same side of the sheet of leather, and free ends at 105 the other side of said sheet of leather, with the adjacent strips having their doubled ends against opposite sides of said sheet of leather and the two ends of the doubled strip being adjacent to each other, and an adhesive layer applied to the free ends of a series of strips.

In testimony that I claim the foregoing, I 110 have hereunto set my hand this 6th day of Feb., 1929.

FRANK BARBER.
